UNITED STATES PATENT OFFICE.

FLORENTINO E. SHARAH Y CANTOS, OF TACLOBAN, PHILIPPINE ISLANDS.

FOUNTAIN PEN.

1,415,718.

Specification of Letters Patent.

Patented May 9, 1922.

Application filed October 3, 1921. Serial No. 505,073.

To all whom it may concern:

Be it known that I, FLORENTINO E. SHARAH Y CANTOS, citizen of the Philippine Islands, residing at Tacloban, Philippine Islands, have invented new and useful Improvements in Fountain Pens, of which the following is a specification.

The object of the invention is to provide a comparatively simple and efficient construction of fountain pen adapted for carrying a plurality of inks of different colors for alternative use, and designed particularly for employment by bookkeepers and others requiring means for making entries or notations at different times and under certain conditions in red and black ink; and furthermore to provide in a pen of this type means for readily controlling the feed alternatively from the reservoirs for the different colored inks and for guarding against leakage and confusion of the contents of the ink reservoirs; and with these objects in view the invention consists in a construction and combination of parts of which a preferred embodiment is shown in the accompanying drawing, wherein:—

Figure 1 is a side view of a pen embodying the invention.

Figure 2 is a central longitudinal sectional view of the same.

The barrel or stock 10 which is of cylindrical or tubular form is divided longitudinally by a partition 11 to form the separate ink reservoirs or chambers 12 and 13, and the tip 14 which carries the pen point 15 is removably attached to one end of said barrel or stock by means of the threaded joint 16, said tip being removable to facilitate the filling of the reservoirs and having the canals 17 and 18 united to form a common feed channel 19 leading to the pen point, said canals being normally closed by means of valves 20 and 21 seated in the inner ends thereof which are respectively in communication with said reservoirs.

Carried by the barrel or stock at the opposite end from the tip is a head 22 having threaded engagement as shown at 23 with the barrel and consisting of the independently revoluble sleeves 24 and 25 carried by a thimble 26. Said sleeves are internally threaded for engagement respectively with the followers 27 and 28 consisting of plugs to which are respectively attached the upper ends of stems 29 and 30

which are connected with the valves. These sleeves should be distinctly marked to indicate the character or color of the inks respectively contained in the reservoirs controlled by the valves actuated respectively thereby, to the end that when ink of a selected color is desired the proper sleeve may be rotated to retract the related follower to open the corresponding valve and thus permit the flow of the selected ink to the pen point, and in order to normally secure the sleeves against rotation to prevent accidental unseating of the valves locking means are provided for the same consisting of the catches 31 and 32 associated respectively with the sleeves 24 and 25 and carried for example, as illustrated in the drawing, by the shank of a pocket clip 33 secured to the barrel or stock.

The upper end of the barrel is fitted with a closure 34 through guide openings in which the valve stems extend, and in contact therewith is an absorbent packing disk 35 of felt or its equivalent to act as a means of preventing leakage beyond the upper end of the barrel, the said packing disk being peripherally elongated by the contact therewith of the lower edge of the sleeve 25.

The invention having been described what is claimed as new and useful is:—

1. A fountain pen having a compartmental tubular barrel or stock fitted at one end with a tip carrying a pen point and at the other end with a head having independently revoluble sleeves, said tip having canals in communication respectively with compartments of the barrel or stock and fitted with controlling valves operatively connected respectively with said sleeves.

2. A fountain pen having a compartmental tubular barrel or stock fitted at one end with a tip carrying a pen point and at the other end with a head having independently revoluble sleeves, said tip having independent canals in communication respectively with the compartments of the barrel or stock and united to form a common feed passage to convey ink to the pen point, and valves for respectively closing said canals operatively connected with said sleeves.

3. A fountain pen having a compartmental tubular barrel or stock fitted at one end with a tip carrying a pen point and at the other end with a head having independently revoluble sleeves, said tip hav-

ing canals respectively in communication with the compartments of the barrel or stock and fitted with controlling valves, and followers actuatable respectively by said sleeves and connected respectively with the stems of said valves.

4. A fountain pen having a compartmental barrel or stock fitted at one end with a removable pen point carrying a tip having ink conveying canals respectively in communication with the compartments of the barrel and fitted at the other end with a head having independently revoluble internally threaded sleeves, valves for respectively closing said canals, followers mounted in and having threaded connection respectively with said sleeves and having connection respectively with the stems of said valves, and means for independently locking said sleeves against rotation.

5. A fountain pen having a compart-

mental barrel or stock fitted at one end with a removable pen point carrying a tip having ink conveying canals respectively in communication with the compartments of the barrel and fitted at the other end with a head having independently revoluble internally threaded sleeves, valves for respectively closing said canals, followers mounted in and having threaded connection respectively with said sleeves and having connection respectively with the stems of said valves, and means for independently locking said sleeves against rotation, said barrel being provided at its upper end with a closure disk through which the stems of the valve extend, and an absorbent packing disk disposed upon said closure disk and held in place by said head.

In testimony whereof he affixes his signature.

FLORENTINO E. SHARAH y CANTOS.
